UNITED STATES PATENT OFFICE.

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK.

MICROPHONE.

Application filed July 18, 1923. Serial No. 652,281.

This invention relates to certain improvements in method and apparatus for translating sound wave variations into corresponding variations of an electric current, which latter variations may be used or translated as desired. Or perhaps differently stated, the invention relates to a method or apparatus for producing variations of an electric current in accordance with or corresponding to sound wave variations, and specifically I term the apparatus a gas-thermo microphone.

The main object of the invention is to produce a highly sensitive instrument that will intensify the sound effect and accurately translate sound waves into corresponding variations of electric current, which latter variations may be re-translated with or without amplification, and with practically perfect quality.

A further and more specific object resides in the elimination of distortion and foreign noises which might result from sympathetic diaphragm vibrations or other causes, and which affect the sound waves to be translated or their transmission.

Other objects and advantages relate to the details of the apparatus, all as will more fully appear from the following description, taken in connection with the accompanying drawings, in which:

Figure 1 is a diagrammatic illustration of the invention with the gas chamber shown in section.

Figure 2 is a front elevation of the gas chamber.

Figure 3 is a diagrammatic view of a peculiar adaptation of my invention.

The invention as shown comprises a substantially flat disk —1— which may perhaps preferably be of circular form, and is provided with an opening —2—, in this disclosure of substantially rectangular form and positioned at substantially the central portion of the disk. Within this opening is arranged a short wire —3— formed of a material that varies its electrical resistance in accordance with its temperature, and the opposite ends of this wire —3— are connected in circuit with the positive and negative sides respectively of a variable source of potential, such as the battery —4—, any suitable means of well known construction being provided for effecting desired variations of

the source of potential utilized for heating the wire —3—.

Within this circuit may be positioned the primary —5— of a transformer, the secondary —6— of which may be connected to suitable amplifying means or directly to any suitable translating means, such as the telephone receivers —7—. Preferably, the wire —3— is of very small diameter, as for illustration, plus or minus .00001", and is in the form of a coil or low pitch spiral, as indicated, and is arranged in the opening —2— in the disk —1—, and for illustrative purposes, this opening —2— may be about one-half an inch long and one-quarter inch wide, and the wire —3— in its spiral form may be approximately one-quarter inch long so as to fit within the opening without contact therewith. However, the opening may be of various shapes, as circular, and the wire instead of being in spiral form may be of varied forms, as straight, and more than one wire —3— may be used if desired.

The disk —1— may, as shown, be formed with an annular flange —8— penetrated by an inlet pipe —9— adapted to carry a gas such as air, or a combination of gases, under pressure from any suitable source of supply, as a blower —10—, and the rate of flow of gas from the pipe —9— is adjusted for the best sensitivity of the apparatus, and may be just below the point where passage of gas through the opening —2— around the wire —3— causes any noise, as for instance, a hissing sound. The sheet —11— of fabric, such as thin silk, may be secured across the open end of the flange —8— in any suitable manner, and may be either taut or loose, so that in effect the rear of the gas chamber is partially open and part of the gas or air may escape therethrough. The remainder of the gas or air entering the gas chamber —12— from the pipe —9— escapes through the opening —2— around the wire —3— and tends to cool the wire at all times. The wire may be formed of any suitable material that varies its resistance to the passage of an electric current in accordance with its temperature, and altho various substances may be used, I have found platinum suitable for the purpose.

Placing the filament in an opening of desired size, such as the opening —2— intensifies the sound effect resultant from the use

of the apparatus and without distortion. Preferably, the disk —1— is used as the front of the apparatus, and is toward the speaker or the sound waves which it is desired to translate, as in this position the sound waves to be translated are coming in a direction substantially opposite to the direction of the movement of the gas escaping through the opening —2—, and acting to cool the spiral wire —3—. This positioning of the instrument is not, however, essential, altho my present experience leads me to believe that a more advantageous result is obtained in that manner.

15 Altho my invention is adapted for many general uses, as for instance in wireless transmission, or in sound or voice translation or reproduction of any purpose, in Figure 2 I have illustrated a peculiar combination embodiment of my invention relating to the translation of variations in sound waves into corresponding variations of light waves which may be translated into a photographic record on a film by means of suitable apparatus, including a wire or member that varies its resistance to the passage of an electric current in accordance with its temperature combined with means for heating the wire and preferably means for causing a current of gas to travel around the wire.

In the construction shown in Figure 2, the secondary —6— of the transformer, instead of being directly connected to a translating device such as the telephone receivers —7— is connected in circuit with the filament —13— and grid —14— of an electroionic discharge device —15—, provision being made for heating the filament, such as a heating circuit including a battery —16—. The filament —13— is further connected to the plate —16— of the device —15— through a source of potential, such as battery —17— with the primary —18— of a transformer, the secondary —19— of which is connected in circuit with the spaced electrodes —20— and —21— respectively, all as shown and described in my co-pending applications Serial No. 614,762, filed Jan. 25, 1923, and Serial No. 616,704, filed Feb. 3, 1923. The photographing means may include, as shown, a filament —21— passing by the comparatively small slot or opening —22— and the concentrating lens —23— if desired. With this construction of apparatus, the variations in sound waves are translated by the resistance of wire —3— into variations of the electric current which are amplified by the electroionic discharge device —15— and its circuits, and are impressed upon the lamp —24—, thereby effecting variations in the light rays emanating from said lamp in accordance with sound wave variations.

The lamp —24— is a preferred illustration of a lamp suitable for my purpose, and may consist of a bulb —25— containing a suit-

able gas, such as helium under pressure, and two or more electrodes of suitable form, as illustrated two in number, the electrode —20— being of substantially cylindrical form and the electrode —21— being in the form of a wire or filament that terminates adjacent the lower end of the cylindrical electrode and is spaced therefrom.

It will be obvious that this lamp may be substituted for the primary —18— of the transformer, and may be connected in circuit with the filament —13— and plate —16— and the transformer —26— entirely omitted, but the construction shown is perhaps preferable for my purpose.

This apparatus constitutes a means for translating sound wave variations into a photographic record of light variations corresponding to said sound wave variations.

Altho I have shown and described a specific construction of apparatus and preferred details thereof, I do not desire to limit myself to any particular form, shape or size of the wire —3— or of the opening —2—, as a considerable variation is possible, nor do I desire to limit myself to the use of a fabric wall —11— such as that illustrated, altho its use may be preferable, the broad idea of this invention residing in the positioning of an element that varies its resistance in accordance with its temperature in an opening in another element through which a stream of air or gas passes under an adjusted pressure suited to the conditions of operation of the instrument.

I claim:

1. In an apparatus of the class described, a gas chamber, means for supplying gas under pressure to said chamber, an outlet from said chamber, and a member that varies its electrical conductivity in accordance with its temperature arranged in said outlet.

2. In an apparatus of the class described, a gas chamber, means for supplying gas under pressure to said chamber, an outlet from said chamber, a member that varies its electrical conductivity in accordance with its temperature arranged in said outlet, and a source of potential in circuit with said member.

3. In an apparatus of the class described, a gas chamber, means for supplying gas under pressure to said chamber, an outlet from said chamber, a member that varies its electrical conductivity in accordance with its temperature arranged in said outlet and said chamber having a wall formed of a porous member.

4. In an apparatus of the class described, a gas chamber, means for supplying gas under pressure to said chamber, an outlet from said chamber, a member that varies its electrical conductivity in accordance with its temperature arranged in said outlet, a source

of potential in circuit with said member, and said chamber having a wall formed of a porous member.

5. In an apparatus of the class described,
5 a gas chamber, means for supplying gas under pressure to said chamber, an outlet from said chamber, a member that varies its electrical conductivity in accordance with its temperature arranged in said outlet, and
10 said chamber having a wall formed of a porous fabric.

15 6. In an apparatus of the class described, a gas chamber, means for supplying gas under pressure to said chamber, an outlet from said chamber, and a member that varies its electrical conductivity in accordance with its temperature exposed to the current of gas escaping through said outlet.

gas escaping through said outlet.

7. In an apparatus of the class described,
20 a disk having an opening therethrough,
means for causing the passage of a forced
current of gas through said opening, and a
wire that varies its electrical resistance in
accordance with its temperature exposed to
25 the current of air escaping through said
opening.

8. In an apparatus of the class described, a disk having an opening therethrough, means for causing the passage of a forced current of gas through said opening, a wire 30 that varies its electrical resistance in accordance with its temperature exposed to the current of gas escaping through said opening, and means for maintaining said wire in a heated condition.

9. In an apparatus of the class described, a disk having an opening therethrough, means for causing the passage of a forced current of gas through said opening, a spiral

wire that varies its electrical resistance in accordance with its temperature exposed to the current of gas escaping through said opening and means for maintaining said spiral wire in a heated condition.

10. In an apparatus of the class described, a gas chamber, means for supplying gas under pressure to said chamber, an outlet from said chamber, a member that varies its electrical conductivity in accordance with its temperature exposed to the current of gas escaping through said outlet, and a source of potential in circuit with said member. 45

11. In an apparatus of the class described, a gas chamber, means for supplying gas under pressure to said chamber, an outlet from said chamber, a member that varies its electrical conductivity in accordance with its temperature exposed to the current of gas escaping through said outlet, and a source of potential in circuit with said member, said member having a wall formed of a porous member. 55
60

12. In an apparatus of the class described, a gas chamber having an opening in its front wall and having its rear wall comprising a porous member, means for supplying gas under pressure to said chamber independently of the opening in the front wall and the pores of the member of the rear wall, a member that varies its electrical conductivity in accordance with its temperature positioned so as to be exposed to the current of gas which passes through said opening. 70

In witness whereof I have hereunto set my hand this 5th day of July, 1923.

THEODORE WILLARD CASE
